UNITED STATES PATENT OFFICE

2,483,651

HYDRAULIC VALVE

Arthur L. Lee, Upper Arlington, Ohio, assignor, by
means assignments, to The Jeffrey Manufacturing Company, a corporation of Ohio

Application October 25, 1945, Serial No. 624,555

6 Claims. (Cl. 277—57)

1

This invention relates to a hydraulic valve, and an object of the invention is to provide an improved hydraulic valve, particularly of the solid or unbored spool type, which in one form of the invention includes a plurality of spools controlling separate double acting hydraulic motors, the valve normally providing a substantial no-load by-pass when all the spools are in their neutral positions; the valve also having a pair of spaced drain passageways and one or more leakage passageways, one or both of which leakage passageways are always isolated from the hydraulic fluid pressure in the drain passageways for all positions of the spools.

A further object of the invention is to provide a single valve having the characteristics generally above defined.

Other objects of the invention will appear hereinafter, the novel features and combinations being set forth in the appended claims.

In the accompanying drawing, the single figure is a sectional view through the body or block of the valve, with the valve spools being shown in elevation.

This application is a continuation in part of my application Serial No. 530,361, filed April 10, 1944, for a Loading machine. Certain of the broad features of the valve are claimed in that application or a division thereof.

The embodiment of the invention which is illustrated includes a main block, body or casting 1 which is shown as a single integral body, though in certain aspects of the invention it may be built up of a plurality of adjacent separable body blocks. Within the block 1 there is a plurality of spools, all except one of which are of similar construction and operate in substantially the same way. Because of this fact each of these similar spools and associated valve block parts will be given similar reference characters.

The block 1 includes a plurality of similar parallel bores 2 which extend entirely therethrough and another bore 3 which is parallel to and spaced from the bores 2 but functions in a slightly different manner, as hereinafter described. At one end of the block 1 the bores 2 and 3 are closed by plugs 4. Within each bore 2 is a solid or undrilled type of spool 5. Bore 3 is provided with a spool 6 which is also solid or undrilled. While I have shown four similar spools 5, it is evident that the number may be increased or decreased as desired.

Substantially adjacent the center of each bore 2 and communicating therewith is a central chamber 7. Located on opposite sides of each

2

central chamber 7 and also communicating with each bore 2 is a feed chamber 8. Each central chamber 7 of the three right-hand bores, as viewed in the single figure of the drawings, is in permanent communication with both of the succeeding feed chambers 8 by means of a branching or bifurcated passageway 9, the passageway 9 obviously also functioning to connect the two feed chambers 8 in parallel. The feed chambers 8 of the right-hand bore 2 are also permanently connected together by a branching or bifurcated passageway 10 which is connected with and derives hydraulic fluid from a feed pipe or conduit 11 which constitutes the feed or delivery conduit from a pump or other source of hydraulic fluid.

Located outwardly of each of the feed chambers 8 is a motor chamber 12 or 13 adapted to be connected to a motor pipe or conduit. For example, each chamber 12 may be connected to one side of a double acting or reversible hydraulic motor, while each chamber 13 is connected to the other side thereof. It is, of course, obvious that the various feed chambers and passageways above described are formed within the main block or body 1.

Outwardly of the motor chambers 12 and 13 and in communication with all of the bores 2 and the bore 3 the block 1 is provided with a pair of discharge or drain chambers or passageways 14 and 15 which come together adjacent the left-hand end of the block 1 and communicate with a discharge or drain pipe or conduit 16. Located outwardly of the drain passageways 14 and 15 and formed in the main block 1 in communication with bores 2 and 3 is a plurality of interconnected leakage chambers or passageways 17 and 18. Associated with the chambers or passageway 17 and in communication therewith is a plurality of oil seals 19 through which the spools 5 and 6 extend.

As hereinafter described more completely the chamber or passageway 17 is entirely free of the pressure of the hydraulic fluid in the system, even including that in the drain passageway 14, and consequently there will be no tendency for the oil seals 19 to blow out or to leak. The leakage chambers or passageways 17 and 18 are both drained to an atmospheric pressure receptacle, thus eliminating any occurrence of pressure therein which is particularly important in connection with the seals 19.

This has solved a problem which was presented by the valve disclosed in my co-pending application above mentioned because in practice there is

frequently a substantial amount of back pressure in the discharge or drain passageways 14 and 15. In practice, this back pressure is often as high as fifty pounds and, in the absence of isolating the seals from such back pressure, they tend to seize the spools, to leak, and to blow out. All of these undesirable characteristics have been overcome in the structure of the present valve.

The central chamber 7 of the last bore 2 measuring from the right to the left, as viewed in the drawing, discharges over parallel passageways 20 to the drain passageways 14 and 15 and this valve is the last of the series of four illustrated in the embodiment of my invention each of which acts as a four-way valve for controlling a reversible or double acting hydraulic motor.

The function of the spool 6 and associated chambers and passageways is merely to provide for the selective reverse connection of a pair of parallel hydraulic motors associated with the last valve spool 5 of the series of four and with the valve spool 6, as hereinafter described in complete detail.

As above mentioned, the construction of each of the spools 5 is the same. Each of said spools includes a central land 21 which, when the spool 5 is in its normal or neutral position, occupies a position in the center of the central chamber 7, and the reduced shank portion of the spool 5 on opposite sides of the land 21 provides adequate clearance through the bore 2 to provide for normal free flow of hydraulic fluid delivered to the passageway 10 into the first central chamber 7 over parallel paths which feed the central chamber 7 from opposite sides.

When all of the spools 5 are in their normal or neutral positions it is evident that a no-load by-pass series circuit is provided through all of the central chambers 7 and through the branching or bifurcated passageways 9 and the portions of bores 2 which interconnect the feed chambers 8 and the central chambers 7; the hydraulic fluid in the last central chamber 7 being discharged to the drain passageways 14 and 15 and the drain conduit 16 by way of the branching passageway 20.

It is to be noted that this no-load by-pass is provided with a solid or unbored type of spool and furthermore a parallel path leading from each feed chamber 8 to a central chamber 7 through a bore 2 and around the spool 5 provides a large cross-sectional area and thus a small resistance to the flow of the hydraulic fluid which produces a small pressure drop through the series of valves.

Each spool 5 is also provided with a pair of spaced lands 22 and 23 which will seal the motor chambers 12 and 13, respectively, when the spools 5 are in their normal or neutral positions, thus locking or trapping the hydraulic fluid on opposite sides of the double acting or reversible motors. Near opposite ends the spools 5 also carry isolating lands 24 and 25 which isolate the chambers or passageways 17 and 18 from the discharge or drain chambers or passageways 14 and 15 for all positions of adjustment of the spools 5, thus entirely isolating the chambers or passageways 17 and 18 and thus isolating the seals 19 from the back pressure of the hydraulic fluid which may appear in the passageways 14 and 15.

The lands 25 are provided not primarily to protect any seals, but primarily to provide for a complete balance of the spools 5 which would

not otherwise be present if the spools were cut off before reaching the lands 25. However, in certain broad aspects of the invention where a completely balanced spool is not necessary the lands 25 may be omitted and the spools 5 and 6 as well as the main block 1 may be foreshortened because of this.

As above mentioned, when each of the spools 5 is in its neutral position there will be a low pressure or no-load by-pass for the fluid through the valve from feed pipe 11 to discharge pipe 16 and the motor chambers 12 and 13 will be sealed. Reverse actuation of the motors connected to chambers 12 and 13 may be produced by reverse movement of the associated spool 5. For example, if a spool 5 is moved upwardly from its neutral position, as viewed in the drawing, the no-load by-pass will be shut off by the lands 21 and 23 filling the bore 2 on opposite sides of the central chamber 7. Simultaneously, the motor chamber 12 will be connected to feed passageway 10 and motor chamber 13 will be connected to drain passageway 15. This, of course, will produce actuation of the associated double acting motor in one direction. Reverse movement of the spool 5 from its neutral position will shut off the by-pass by the action of lands 21 and 22, while chamber 13 is connected to the feed passageway 10 and chamber 12 is connected to discharge passageway 14.

The action of each of the spools 5 is essentially the same. The spool 6 is of different construction as is its associated chambers and passageways and its relation to the adjacent spool 5 is substantially the same as disclosed and claimed in my parent application above identified or a division thereof.

Briefly described, it is as follows. The bore 3 has a central chamber 26 associated therewith formed in the block 1. On opposite sides of the central chamber 26 is a pair of feed chambers 27 and 28 also in communication with the bore 3. Outwardly of the feed chambers 27 and 28 and communicating with the bore 3, block 1 is provided with interconnecting reversing chambers 29 and 30 interconnected by a passageway 31. Block 1 is also provided with passageways 32 and 33 which interconnect the motor chambers 12 and 13 of the last or left-handmost reversing valve 2, 5 with the feed chambers 27 and 28 of the reversing valve 3, 6.

The spool 6 has a relatively wide central land 34 and a pair of spaced end lands 35, 36. The central chamber 26 is a motor chamber and the parallel connected chambers 29 and 30 are also motor chambers, being common to a single fitting or conduit. The spool 6 is only a two position spool rather than a three position spool as are the spools 5. Its function is to reverse the relative connection between the double acting motors associated with the valve 3, 6 and with the left-handmost valve 2, 5. For example, with the spool 6 in the position illustrated, the chamber 12 of the left-handmost valve 2, 5 is connected in parallel with motor chamber 29, while chamber 13 of said left-handmost valve 2, 5 is connected in parallel with the chamber 26. This is one normal position of the spool 6. The other is achieved by moving the spool 6 downwardly as viewed in the drawing, under which circumstances motor chamber 12 of said valve 2, 5 is connected in parallel with the central chamber 26 and motor chamber 13 is connected in parallel with the motor chamber 29 by way of motor chamber 30 and passageway 31.

From the above description, a number of characteristics of the valve are evident. First of all,

the valve is of the sliding spool type, the sliding spool being solid or undrilled. When the valves are in their normal positions they provide a no-load by-pass between the feed conduit 11 and the discharge conduit 16, thus substantially unloading any pump which may be continuously driven in the hydraulic system with which the valve is associated. The operation of any spool 5 automatically shuts off this series circuit no-load by-pass and supplies hydraulic fluid under pressure to a motor chamber connecting the associated motor chamber to drain. A reverse operation of a spool 5 from its neutral position selectively connects an associated pair of motor chambers to drain and pressure. The spools are entirely balanced even as to any back pressure which may be present in the drain passageways 14 and 15 and it is particularly because of the occurrence of back pressure in such passageways that the isolating lands 24 and 25 are provided, the former to protect oil seals 19, the latter when employed to provide substantially complete balance on the spools 5.

While the block 1 is a unitary block to accommodate a plurality of valves, the complete assembly may, if desired, be built up of individual blocks, one for each spool 5. By the same token, in certain aspects of the invention it may relate to a single spool 5 and associated valve body, though in a more complete aspect of the invention it relates to a valve body either unitary or built up which accommodates a plurality of similar valve spools 5. This is particularly true in view of the series no-load by-pass which is provided, involving the branching or bifurcated passageways 9 which lead to the central chambers 7 from opposite sides through the bores 2.

Obviously those skilled in the art may make various changes in the details and arrangement of parts without departing from the spirit and scope of the invention as defined by the claims hereto appended, and I therefore wish not to be restricted to the precise construction herein disclosed.

Having thus described and shown an embodiment of my invention, what I desire to secure by Letters Patent of the United States is:

1. A multiple spool hydraulic valve for controlling a plurality of hydraulic motors including a valve body, a plurality of spaced valve bores in said body, a solid type valve spool slidable in each valve bore, each valve bore having a central chamber communicating therewith, a pair of feed chambers communicating therewith and located on opposite sides of said central chamber and normally both communicating with said central chamber when the associated spool is in its neutral position, passageways connecting each central chamber with the pair of feed chambers of an adjacent bore, the above defined construction providing a continuous feed passageway through all of said bores and passageways with each central bore being fed through a pair of passageways and feed chambers and through a valve bore from opposite sides of the central chamber, each of said valve bores also having a pair of motor chambers communicating therewith and located outwardly of said feed chambers, a pair of parallel drain passageways located outwardly of said motor chambers and communicating with said valve bores, seals for said valve bores communicating with said leakage passageway and through which said spools extend, lands on said spools communicating with said leakage passageway and through which said spools extend, lands on said

spools which continuously isolate said leakage passageway from the pressure of fluid in said drain passageways for all positions of adjustment of said spools, and lands on each spool operative on reverse movements thereof from its neutral position to connect one motor chamber to one of said drain passageways and connect the other motor chamber to a feed chamber.

2. A multiple spool hydraulic valve for controlling a plurality of hydraulic motors including a valve body, a plurality of spaced valve bores in said body, a solid type valve spool slidable in each valve bore, each valve bore having a central chamber communicating therewith, a pair of feed chambers communicating therewith and located on opposite sides of said central chamber and normally both communicating with said central chamber when the associated spool is in its neutral position, passageways connecting each central chamber with the pair of feed chambers of an adjacent bore, the above defined construction providing a continuous feed passageway through all of said bores and passageways with each central bore being fed through a pair of passageways and feed chambers and through a valve bore from opposite sides of the central chamber, each of said valve bores also having a pair of motor chambers communicating therewith and located outwardly of said feed chambers, a pair of parallel drain passageways located outwardly of said motor chambers and communicating with said valve bores, a pair of leakage passageways spaced outwardly of said drain passageways and communicating with said valve bores, seals for said valve bores communicating with one of said leakage passageways and through which said spools extend, lands on said spools which continuously isolate said leakage passageways from the pressure of fluid in said drain passageways for all positions of adjustment of said spools, and lands on each spool operative on reverse movements thereof from its neutral position to connect one motor chamber to one of said drain passageways and connect the other motor chamber to a feed chamber.

3. A hydraulic valve including a body having a valve bore therein, a solid type valve spool slidable in said bore, a central chamber communicating with said bore, a pair of feed chambers communicating with said bore and located on opposite sides of said central chamber and normally both communicating therewith when said spool is in its neutral position, a feed passageway connecting said pair of feed chambers in parallel, a pair of motor chambers communicating with said valve bore and located outwardly of said feed chambers, a pair of drain passageways located outwardly of said motor chambers and communicating with said valve bore, a seal for said valve bore communicating with one of said leakage passageways and through which said spool extends, lands on said spool which continuously isolate said leakage passageways from the pressure of fluid in said drain passageways for all positions of adjustment of said spool, and lands on said spool operative on reverse movements of said spool from its neutral position to connect a motor chamber to one of said drain passageways and connect the other motor chamber to a feed chamber.

4. A hydraulic valve including a body having a valve bore therein, a solid type valve spool

slidable in said bore, a central chamber communicating with said bore, a pair of feed chambers communicating with said bore and located on opposite sides of said central chamber and normally both communicating therewith when said spool is in its neutral position, a feed passageway connecting said pair of feed chambers in parallel, a pair of motor chambers communicating with said valve bore and located outwardly of said feed chambers, a pair of drain passageways located outwardly of said motor chambers and communicating with said valve bore, a leakage passageway spaced outwardly of at least one of said drain passageways and communicating with said valve bore, a seal for said valve bore communicating with said leakage passageway and through which said spool extends, a land on said spool which continuously isolates said leakage passageway from the pressure of fluid in said drain passageways for all positions of adjustment of said spool, and lands on said spool operative on reverse movements of said spool from its neutral position to connect a motor chamber to one of said drain passageways and connect the other motor chamber to a feed chamber.

5. A hydraulic valve including a body having a valve bore therein, a solid type valve spool slidable in said bore, a pressure chamber, a pair of spaced motor chambers communicating with said valve bore, a pair of drain chambers located outwardly of said motor chambers and communicating with said valve bore, a pair of leakage passageways spaced outwardly of said drain chambers and communicating with said valve bore, a seal for said valve bore communicating with one of said leakage passageways and through which said spool extends, lands on said spool which continuously isolate said leakage passageways from the pressure of fluid in said

30

35

40

drain chambers for all positions of adjustment of said spool, and means including lands on said spool operative on reverse movements of said spool from its neutral position to connect a motor chamber to one of said drain passageways and to connect the other motor chamber to the pressure chamber.

6. A hydraulic valve including a body having a valve bore therein, a solid type valve spool slidable in said bore, a pressure chamber, a pair of spaced motor chambers communicating with said valve bore, a pair of drain chambers located outwardly of said motor chambers and communicating with said valve bore, a leakage passageway spaced outwardly of at least one of said drain chambers and communicating with said valve bore, a seal for said valve bore communicating with said leakage passageway and through which said spool extends, lands on said spool which continuously isolate said leakage passageway from the pressure of fluid in said drain chambers for all positions of adjustment of said spool, and means including lands on said spool operative on reverse movements of said spool from its neutral position to connect a motor chamber to one of said drain passageways and to connect the other motor chamber to the pressure chamber.
